UNITED STATES PATENT OFFICE

139,131

DESIGN FOR A CHAIR STOOL OR SIMILAR ARTICLE

Velden J. Sullivan and James Alastra,
Gooding, Idaho

Application July 25, 1944, Serial No. 114,551

Term of patent 14 years

(Cl. D15—8)

To all whom it may concern:

Be it known that we, Velden J. Sullivan and James Alastra, both citizens of the United States and both residing at Gooding, in the county of Gooding and State of Idaho, have invented a new, original, and ornamental Design for a Chair Stool or Similar Article, of which the following is a specification, reference being had to the accompanying drawing, forming a part hereof.

Figure 1 is a side elevational view of a chair stool, showing my new design;

Figure 2 is a top plan view, and

Figure 3 is an end elevational view thereof.

We claim:

The ornamental design for a chair stool or similar article, as shown.

VELDEN J. SULLIVAN.
JAMES ALASTRA
